CLAIM

The ornamental design for an eyeglass clasp for pocket clip, as shown and described.

DESCRIPTION

FIG. 1 is a front perspective view of a eyeglass clasp for pocket clip showing my new design, the broken line showing of the pocket clip portion is for illustrative purposes only and forms no part of the claimed design;

FIG. 2 is a front elevational view thereof;

FIG. 3 is a top plan view thereof;

FIG. 4 is a rear elevational view thereof;

FIG. 5 is bottom plan view thereof;

FIG. 6 is a left side view thereof; and

FIG. 7 is a right side view thereof;

FIG. 8 is a second modified embodiment of the design shown in FIGS. 1-7.

FIG. 9 is a front elevational view thereof;

FIG. 10 is a top plan view thereof;

FIG. 11 is a rear elevational view thereof;

FIG. 12 is a bottom plan view thereof;

FIG. 13 is a left side view thereof; and,

FIG. 14 is a right side view thereof.
